UNITED STATES PATENT OFFICE.

ERASTUS E. WINKLEY, OF LYNN, MASSACHUSETTS.

STEERING APPARATUS.

Application filed September 28, 1920. Serial No. 413,448.

To all whom it may concern:

Be it known that I, ERASTUS E. WINKLEY, a citizen of the United States, residing at Lynn, in the county of Essex and State of Massachusetts, have invented certain new and useful Improvements in Steering Apparatus; and I do hereby declare the following to be a full, clear, and exact description of the invention, such as will enable others skilled in the art to which it appertains to make and use the same.

The present invention relates to controlling apparatus for moving objects, and more particularly to apparatus acting automatically to guide or steer a moving object such as a vessel, flying machine, or torpedo upon a predetermined course of one or more legs.

The object of the present invention is to provide a novel and improved apparatus of this type which is simple in construction and certain and reliable in operation.

The features of the present invention consist in certain constructions, arrangements and combinations of parts hereinafter described and claimed, the advantages of which will be obvious to those skilled in the art.

The several features of the present invention will be clearly understood from the following description and accompanying drawings, in which:—

Figure 1 is a diagrammatical plan view of a vessel having a guiding or steering apparatus applied thereto embodying the features of the invention in their preferred form; Figs. 2 and 3 are plan and side views, partly in section, of the actuating mechanism for the rudder or guiding device of the vessel; Fig. 4 is a detail side elevation of a switch forming a part of the rudder actuating mechanism; Fig. 5 is a detail sectional view taken on the line 5—5 of Fig. 2; Fig. 6 is a detail sectional view on an enlarged scale of a switch taken on the line 6—6 of Fig. 3; Fig. 7 is a plan view of the controlling mechanism embodying a compass for controlling the operation of the rudder actuating mechanism; Figs. 8 and 9 are side and end elevations of the portion of the apparatus illustrated in Fig. 7; Fig.

10 is a sectional view taken on the line 10—10 of Fig. 7; Fig. 11 is a plan view of the course setting mechanism of the apparatus; Fig. 12 is a detail side elevation of a switch forming a part of the mechanism illustrated in Fig. 11; Fig. 13 is a rear elevation of the course setting mechanism; Fig. 14 is a sectional plan view taken on the line 14—14 of Fig. 13.

In Fig. 1 of the drawings, an apparatus embodying the present invention is shown applied to a vessel 2 having a rudder 4. The apparatus is adapted to operate and control the rudder to steer the vessel on a given course of one or more legs that has been laid out on a course setting mechanism forming a part of the apparatus. When the direction of travel of the vessel is to be changed either to restore the vessel to the given course upon a deviation therefrom or to direct the vessel upon a new leg of its course, the rudder is turned from the neutral position shown in Fig. 1 to the right or left to direct the vessel to port or starboard as the case may be. The rudder is held in the position moved until the desired change in the direction of travel of the vessel has been accomplished, whereupon the rudder is returned to neutral position.

The rudder is operatively connected with a windlass 6 by a cable 8 that passes over suitably arranged idle pulleys 10. The windlass 6 is secured to the rear end of a shaft 12 which is journaled in a casing or frame 14 and forms a part of the rudder actuating mechanism. Upon rotation of the shaft 12 to the right, the rudder 4 is turned in the direction to steer the vessel to starboard and upon rotation of the shaft 12 to the left the rudder is turned in the direction to steer the vessel to port. The shaft 12 is actuated by a continuously driven shaft 16 (Figs. 2 and 3) journaled in a bearing in the rear wall of a casing 14. The shaft 16 constitutes the main driving shaft of the apparatus and is driven by a pulley 18 either from the propeller shaft of the vessel or from a separate power plant. The connection between the shaft 12 and the driving shaft 16 comprises a worm wheel 20 secured

to the shaft 12 which is engaged by a worm 22 carried by a shaft 24 having its ends journaled in the casing 14. A pair of oppositely disposed bevelled gears 26 and 28 are loosely mounted on the shaft 24 and are driven in opposite directions by engagement with a bevelled gear 30 carried by the driving shaft 16. When the vessel is to be steered to starboard, the bevelled gear 26 is clutched to the shaft 24, and when the vessel is to be steered to port the bevelled gear 28 is clutched to the shaft 24. The means for clutching the gears 26 and 28 to the shaft 24 comprises a double clutch member 32 keyed to the shaft 24. Upon shifting the clutch member 32 to the left, the gear 26 is clutched to the shaft 24 by the engagement of the clutch member with clutch pins 34 secured to the gear, and upon shifting the clutch member 32 to the right the gear 26 is clutched to the shaft by the engagement of the clutch member with clutch pins 36 secured to the gear. The clutch member is shifted by means of a lever 38 centrally pivoted on a pin 40 secured to the frame of the apparatus. The forward end of the lever 38 is bifurcated and is provided with studs or rolls that engage an annular groove in the clutch member 32, and the rear end of the lever 38 is bifurcated to engage between collars 42 secured to a longitudinally movable rod 44. The rod 44 is shifted in a direction to clutch the gear 26 to the shaft 24 by the engagement of the inner end of a double pawl 46 with a collar 48 secured to the rod and is shifted in the opposite direction to bring the clutch member 32 to neutral position by the engagement of the outer end of the pawl 46 with a collar 50 secured to the rod 44. The rod is shifted in the direction to clutch the bevelled gear 26 to the shaft 24 by the engagement of the inner end of a double pawl 52 with a collar 54 secured to the rod 44 and is shifted in the opposite direction to return the clutch member 32 to neutral position by the engagement of the outer end of the pawl 52 with a collar 56 secured to the rod. The pawls 46 and 52 are secured to pins 58 having their ends extending through and pivotally mounted in apertures in the members of forked arms 60 and 62, respectively, pivotally mounted at their lower ends on pivot pins 63 supported by the frame. The forked arms 60 and 62 are constantly oscillated in opposite directions to move the pawls longitudinally of the rod 44 by means of a rod 64 having its ends pivotally connected to the upper ends of the arms. The rod 64 is actuated by a cam 68 secured to the driving shaft 16. The connection between the cam 68 and the rod 64 comprises an arm 70 having its lower end bifurcated to operatively engage the cam and its upper end secured to a rock shaft 72 having its ends mounted in the casing 14.

An arm 74 is also secured to the rock shaft 72 and has its lower end connected with the rod 64. In order to insure that the clutch member 32 may properly engage the clutch pins carried by the gears 26 and 28 when the clutch member is shifted in either direction, the arm 74 is yieldingly connected to the rod 64. To this end the lower end of the arm 74 is bifurcated to engage between collars 76 which are yieldingly urged toward the end of the arm 74 by means of springs 78 coiled about the rod and interposed between the collars 76 and nuts 80 threaded on the rod, the movement of the collars by the action of the springs being limited by pin-and-slot connections between the collars and the rod.

When the vessel is directed upon its course the pawls 46 and 52 are held by gravity in the position shown in Fig. 3 which locates their outer ends in position to engage the collars 50 and 56 through which the clutch member 32 is shifted to neutral position.

To turn the rudder in a direction to steer the vessel to port, the pawl 46 is turned in the direction to bring its inner end into position to engage the collar 48, whereupon on the next inward movement of the oscillating arm 60, the pawl 46 will act through the collar 48 to move the rod 44 in the direction to clutch the gear 26 to the shaft 24. Likewise, to turn the rudder in the direction to steer the vessel to starboard, the pawl 52 is turned in the direction to bring its inner end into position to engage the collar 54. The pawls 46 and 52 are thus positioned to swing the vessel to starboard and port by means of electro-magnets 82 and 84 mounted on brackets secured to the casing 14, which magnets act on armatures 86 and 87 formed on the ends of arms secured to the pivot pins carrying the pawls 46 and 52, respectively. The electro-magnets are included in independent circuits with controlling devices hereinafter described. Upon a circuit being closed by the controlling devices, the electro-magnet included in the circuit acts to position the associated pawl to turn the rudder. When the rudder has been turned a fixed distance to starboard or port according to which magnet is included in the circuit, the circuit is opened to permit the pawl to be turned by gravity to its normal position to shift the clutch member to neutral position, the rudder being held in the position moved by the worm wheel and worm connection 20, 22. The circuits are opened at this time by means of switches 90 and 92 controlling the electro-magnets 82 and 84, respectively. The switches 90 and 92 each comprises a movable switch member 94 and a stationary switch member 96. The movable switch member 94 comprises a disk secured to the shaft 12 and is provided with a raised peripheral contact portion 98. The

stationary switch member 96 comprises an arm loosely mounted on the shaft 12 and held in fixed position by being secured at its upper end to a bracket 100 secured to the casing 14. A contact pin 102 is mounted to slide in an insulated bushing in the lower end of the arm, the inner end of which pin is adapted to engage the contact portion of the movable switch member 94 and is urged 5 toward the movable switch member by means of a leaf spring 104 secured to the arm and engaging the outer end of the pin, the movement of the pin by the spring being limited, when the pin is out of engagement with the 10 contact portion of the movable member, by means of a head formed on the outer end of the pin engaging the outer end of the insulated bushing.

It will be apparent from an inspection of 20 the drawings, that upon rotation of the shaft 12 to the right, viewing Fig. 3, the rudder is turned in the direction to swing the vessel to starboard, and upon rotation of the shaft to the left, the rudder is turned 25 in the direction to swing the vessel to port.

During the rotation of the shaft 12 to the right the switch 90 is closed by the engagement of the contact pin 102 thereof with the contact portion 98 of the movable switch member, but when the rudder has been turned 30 a certain fixed distance the rear end of the contact portion 98 passes the pin 102 thereby opening the circuit that includes the switch 90 and the electro-magnet 82. During 35 the rotation of the shaft 12 to the left the switch 92 is closed by the engagement of the contact pin 102 thereof with the contact portion 98, but when the rudder has been turned a fixed distance to the left, the rear end of 40 the contact portion 98 passes the pin 102, thereby opening the circuit that includes the switch 92 and the electro-magnet 84.

The illustrated apparatus has provision for varying the distance that the rudder is 45 turned to the right or left from neutral position. To this end the stationary members 96 of the switches 90 and 92 are adjustable about the shaft 12 to vary the distance that the contact pins 102 are from the rear ends 50 of the contact portions 98 when the rudder is in neutral position. In order to effect such adjustment of the stationary members 96, the members are adjustably secured to the brackets 100 by means of screws 106 extending through slots in the brackets which 55 slots are concentric with the shaft 12.

To return the rudder to neutral position from its fixed angular position to the right or left when the change in direction of 60 travel of the vessel has been completed, the controlling devices act to close a circuit including the proper magnet 82 or 84 that is adapted to move the rudder in this direction. The movement of the rudder is stopped 65 when the rudder reaches its neutral posi-

tion by a switch 108 acting to open the circuit. This switch comprises a movable member 110 and a stationary member 112 (see Fig. 4). The movable member comprises a drum secured to the forward end 70 of the shaft 12 having contact plates 114 and 116 secured to the periphery thereof, the ends of which plates are separated and the plates are insulated from each other. The stationary member 112 comprises a 75 spring contact secured to and insulated from the casing 14 and having its free end arranged to engage the periphery of the movable member 110. The contact plate 114 of the movable member is in circuit with the 80 electro-magnet 82 and the contact plate 116 is in circuit with the electro-magnet 84. When the rudder is in neutral position the shaft 12 will be in such angular position that the stationary switch member 112 will 85 engage between the ends of the plates 114 and 116 and the switch will be open. When, however, the rudder is out of neutral position the stationary switch member will be in 90 engagement with one or the other of the plates 114 and 116 according to whether the rudder is to the left or right of its neutral position. With this construction, when the rudder is out of neutral position and the 95 circuit including the stationary switch member and the contact plate with which it is in contact is closed by the controlling device, the proper electro-magnet 82 or 84 will act to return the rudder to neutral position, and when the rudder has reached neutral 100 position, the circuit will be opened by the contact plate disengaging from the stationary switch member.

From the foregoing it will be apparent 105 that the electro-magnets 82 and 84 are alternately energized; first to swing the rudder from neutral position to a fixed angular position to the right or left to change the direction of travel of the vessel, and when the 110 change in direction of travel of the vessel has been completed, the other magnet is energized to restore the rudder to neutral position. The closing of the circuits of the 115 electro-magnets is effected by the controlling devices of the apparatus presently to be described, while the opening of the circuits is accomplished by the switches 90 and 92 to limit the movement of the rudder from neutral position to a fixed position to the right or left, and the circuits are opened by the switch 108 upon restoring the rudder to neutral position.

The circuit including the magnet 82 and the switch 90 comprises a battery 117 having one terminal connected with the controlling devices of the apparatus and its other terminal connected by a wire 118 with a contact brush 119 engaging the shaft 12, the brush being connected by the shaft with 125 the movable member 94 of the switch 90.

The contact pin of the stationary member of the switch is connected by a wire 120 with one pole of the electro-magnet 82, the other pole of the magnet being connected by a 5 wire 121 with the controlling devices.

The circuit of the magnet 84 and the switch 92 includes the described battery connection with the shaft 12 which is connected by the shaft to the movable switch 10 member of the switch 92. The contact pin 102 of the stationary member of the switch 92 is connected by the contact spring 104 and a wire 122 with one pole of the electro-magnet 84, the other pole of the electro-magnet 15 being connected by a wire 123 that leads to the controlling devices.

The circuit including the electro-magnet 82 and the switch 108 comprises the battery connection with the shaft 12, the switch 90, 20 the wire 120, the wire 121, and a branch wire 124 leading from the wire 121 to a contact brush 125 engaging the contact plate 114 of the switch 108, the stationary member 112 of the switch being connected 25 by a wire 126 with the controlling devices.

The circuit of the electro-magnet 84 and the switch 108 includes the battery connection with the shaft 12, the switch 92, the wire 122 connecting the switch with one 30 pole of the electro-magnet 84, the wire 123, and a branch wire 127 connected to a stationary contact brush 128 that engages the contact plate 116 of the switch 108.

The illustrated mechanism for restoring 35 the vessel to the predetermined course upon deviation therefrom due to an exterior force, such as winds, currents or tides, comprises a compass and mechanism controlled by the compass (Figs. 7, 8, 9 and 10). The compass comprises a compass card 129 centrally pivoted on a post 130 secured to the compass bowl 131. The compass bowl is pivotally mounted by means of gimbal pins 132 and 134 projecting therefrom which extend 40 through apertures in a gimbal ring 136 and are pivotally mounted in sliding sleeves 138. The mounting for the gimbal ring 136 comprises elongated gimbal pins 140 and 142 pivotally mounted at their ends on the ends 45 of screws secured to a compass box 144. A gage 146 is carried by the compass card having peripheral portions that are intermittently engaged by a continually reciprocating feeler 148 that is moved about the 50 gage and compass card with the compass box and vessel. As illustrated in the drawings, the gage has three peripheral feeling portions 150, 152 and 154. With this construction it will be apparent from an inspection 55 of Fig. 7 that upon deviation of the vessel to starboard of its course the feeler 148 will be positioned to engage the portion 154 of the gage; upon deviation of the vessel to port the feeler will be positioned to 60 engage the portion 150; and upon the vessel

being restored to its predetermined course, the feeler will be positioned to engage the portion 152. The connection between the feeler and the rudder actuating mechanism is such that upon engagement 70 of the feeler 148 with the portion 154 of the gage, the rudder will be turned in a direction to swing the vessel to port and upon engagement of the feeler with the portion 150, the rudder will be turned in a direction to 75 swing the vessel to starboard. When the vessel has been restored to its course, the engagement of the feeler with the portion 152 will return the rudder to neutral position. 80

The feeler 148 comprises a rod that extends through an aperture in the compass bowl, the rear end of which rod is secured to the sliding sleeve 138. The sleeve 138 is reciprocated to reciprocate the feeler by 85 means of a bell crank 156 pivoted at 158 on a bracket secured to the gimbal ring 136. The end of one arm of the bell crank engages between collars formed on the sleeve 138 and the end of the other arm of the 90 bell crank engages between collars formed on a sleeve 160 mounted to slide on the gimbal pin 140 of the gimbal ring. The upper end of a lever 162 also engages between the collars on the sleeve 160, which lever is pivoted at 164 on a post projecting 95 upwardly from the bottom of the compass box. The lever 162 is turned in a direction to move the feeler into engagement with the gage 146 by means of a light spring 166 100 connected with the lower arm of the lever, and the lever is turned in the opposite direction to retract the feeler from the gage by means of a continuously rotating cam 168 that acts on a cam roll on the lower end 105 of the lever. The cam is carried by a shaft 170 having its ends journaled in bearings in the end walls of the compass box. The shaft 170 is driven by a large gear 172 secured thereto which meshes with a pinion 110 174 secured to a counter shaft 176 journaled in bearings in the compass box. The shaft 176 extends through the forward end wall 115 of the compass box and is driven by a vertical shaft 178 journaled in bearings beneath the compass box. The connection between the counter shaft 176 and the shaft 178 comprises a belt 180 that passes over pulleys 182 secured to the shaft, the belt being guided by the stretches of the belts passing over idle pulleys 186 loosely mounted on a stud shaft 188 supported by brackets projecting from the compass box. 120

In order to prevent relative rotary movement of the gage and feeler when the feeler 125 is in engagement with the gage, means is provided for locking the gage and compass card at the start of the feeling movement of the feeler and to unlock the gage and card during the retracting movement of the 130

feeler. This means consists of a compass card gripping device 190 comprising a pair of levers 192 pivoted on a boss projecting from the compass bowl, from which boss the 5 gimbal pin 134 extends. Gripping jaws are formed on the inner ends of the levers 192 and are arranged at opposite sides of the compass card. The gripping jaws are actuated at the proper time to engage the 10 card by means of the sleeve 138 through which the gimbal pin 134 extends. The sleeve 138 is reciprocated on the pin 134 and during the outward movement of the sleeve 138, a collar 194 formed on the inner end 15 of the sleeve engages inwardly extending cam surfaces formed on the outer ends of the levers 192 to turn the levers in a direction to cause their gripping jaws to firmly engage the card. During the inward 20 movement of the sleeve 138, the collar 194 permits the levers to be turned in the direction to open the jaws by means of a U-shaped wire spring 196 connecting the rear ends of the gripping levers 192. The sleeve 25 138 is thus reciprocated by means of a bell crank 198 pivoted at 200 on a bracket secured to the gimbal ring 136. The end of one arm of the bell crank 198 engages between collars formed on the sleeve 138, and 30 the end of the other arm of the bell crank engages between collars 202 formed on a sleeve 204 mounted to slide on the gimbal pin 142. The upper end of a lever 206 also engages between the collars 202 on the sleeve 35 204, which lever is pivoted at 208 on an upright post projecting from the bottom of the compass box. The lever 206 is turned in the direction to move the sleeve 138 outwardly to cause the compass card to be locked by 40 means of a coiled spring 212 connected with the lower arm of the lever. The lever 206 is turned in the opposite direction to release the compass card by means of a cam 210 carried by the continuously rotating 45 shaft 170 which cam engages a cam roll at the lower end of the lever 206.

The connection between the gage feeler and the rudder actuating mechanism comprises a switch 213 which consists of a movable switch member 214 and three stationary contacts. The movable member 214 comprises a spring arm that is secured to and insulated from one arm of a lever 222. The spring arm is electrically connected by 50 a pivotal connection 224 with a binding post 226 secured to the rear wall of the compass box. The movable switch member 214 is connected through the post 226, the battery 117 and the wire 118 with the contact brush 119 that engages the windlass and switch carrying shaft 12. The contacts 216, 218 and 220 comprise upstanding metal strips, the lower ends of which are secured to and insulated from a bracket 230 projecting 55 from the rear wall of the compass box. The

contact 216 is connected by the wire 121 to the magnet 82. With this construction, when the movable switch member 214 is brought into engagement with the contact 216, the magnet 82 will be energized to 70 turn the rudder in a direction to swing the vessel to starboard. When the switch member 214 is moved into engagement with the contact 218, the rudder will be returned from starboard to neutral position, the contact 218 being in circuit with the contact plate 116 of the rudder restoring switch 108, through the wire 126 and stationary switch member 112. Upon moving the switch member 214 into engagement with the contact 220, the rudder will be turned in the direction to swing the vessel to port, the contact 220 being connected by the wire 123 with the electro-magnet 84. Upon returning the switch member 214 into engagement 80 with the contact 218, the rudder will be restored to its neutral position, the contact 218 then being in circuit with the contact plate 114 of the switch 108 through the wires 126 and stationary switch member 112. 85

A locking device 232 is provided for clamping the movable switch member 214 down upon a stationary contact of the switch 213 when the movable switch member is positioned over a stationary contact. 90 This locking device comprises a plate 234 extending over the extreme inner end of the movable contact arm, which plate is secured to the upper end of a vertical rod 236 extending through a bearing on the bracket 230. The plate 234 is urged downwardly to clamp the movable switch member 214 on a stationary contact by means of a spring 238 coiled about the rod and interposed between the underside of the bracket 230 and a collar 240 secured to the rod. The rod 236 is moved upwardly to disengage the clamping plate 234 from the contact arm 214 by means of a cam surface 242 formed on the periphery of the cam disk 168. The connection between the rod 236 and the cam 242 comprises a stud 244 mounted on the free end of an arm 246 that is secured to a rock shaft 248. The rock shaft 248 is mounted in bearings in the compass box 105 and has an arm 250 secured to its inner end, which arm carries a cam roll that engages the cam 242.

The movement of the movable switch member 214 into engagement with the stationary contacts of the switch to control the operation of the rudder actuating mechanism is in turn controlled by the gage feeler 148. The connection between the movable switch member 214 and the feeler 148, comprises a link 252 connecting the outer end of the lever 222 that carries the switch member 214 with the outer end of a lever 254 pivoted on a post projecting upwardly 120 from the bottom of the compass box, and the 125

inner end of the lever 254 is adapted to be engaged by a collar 256 formed on the sliding sleeve 160.

- In Fig. 7 the movable switch member 214 is shown clamped down upon the stationary contact 218 of the switch. At the start of a feeling movement of the feeler 148, the locking device 232 releases the switch member 214 allowing the lever 254 to be turned 10 by a coiled spring 258 connected with the lower arm of the lever, in the direction to cause the upper end of the lever to move into engagement with the collar 256, which through the link 252 moves the switch member 214 inwardly to a position inside of the stationary contacts substantially as illustrated by dotted lines in Fig. 7. As the gage feeler moves inwardly toward the gage, the slide 160 is moved outwardly carrying 20 the free end of the lever 254 therewith which moves the switch member 214 to a position over one or another of the stationary contacts of the switch whereupon the locking device 232 acts to clamp the switch member 214 down upon the contact over which it is positioned. If the feeler engages the portion 150 of the gage, the switch member 214 will be positioned over the stationary contact 216 and the rudder will be turned to swing the vessel to starboard; if the gage feeler engages the portion 152 of the gage the switch member 214 will be positioned over the contact 218 and the rudder will be restored to neutral position; and if 30 the gage feeler engages the portion 154 of the gage the switch member 214 will be positioned over the stationary contact 220 and the vessel will be swung to port. It will be understood from the foregoing description 35 that at the limit of the feeling movement of the gage feeler, the switch member 214 will be positioned over one of the contacts and the locking device 234 will be actuated to clamp the switch member down upon the stationary contact, and just before the start 40 of the feeling movement of the feeler, the clamping device will release the switch member, allowing it to be swung by the spring 258 to one side of the contacts.
- 45 It will be obvious from the foregoing that if the compass box is turned about the compass and relatively to the vessel that the direction of travel of the vessel will be changed in accordance with the direction 50 that the compass box is turned and to the extent that the compass box is turned. For example, viewing Fig. 7, if the compass box is turned to a position to the left, the gage feeler will engage the portion 150 of the gage, whereupon the rudder actuating mechanism will act to turn the rudder in the direction to swing the vessel to starboard until the direction of travel of the vessel has 55 changed sufficiently to bring the gage feeler into position to engage the portion 152 of

the gage. If, on the other hand, the compass box is turned to a position to the right, viewing Fig. 7, the gage feeler will engage the portion 154 of the gage, whereupon the rudder actuating mechanism will act to turn the rudder to swing the vessel to port. The amount of change in the direction of travel of the vessel will obviously be in accordance with the amount that the angular position of the compass box is changed relatively to 75 the vessel.

The compass box in the illustrated apparatus is mounted for rotary movement through a limited distance about the compass card and relatively to the vessel, and mechanism is provided for thus changing the position of the compass box, which mechanism is controlled by a course setting device hereinafter described. The compass box is securely mounted upon a table 264 that is mounted on a ball-bearing 266 supported by a cylindrical stationary base 268. In order that the turning of the compass box will not interfere with the electrical connections between the switching device 213 and the rudder actuating mechanisms, the electrical connections are made through contact brushes 269 mounted on the turn table 264 and insulated therefrom, that engage ring contacts 270 mounted on the periphery of the base 268 and insulated therefrom.

The mechanism for turning the compass box to change the angular position thereof relatively to the vessel comprises a large pulley 271 forming a part of the compass box table 264, which pulley is connected to a corresponding pulley 272 by means of a cord belt 274 passing over the pulleys. The pulley 272 is secured to the lower end of a vertical shaft 276 journaled in bearings in a frame 278 (Figs. 11 to 14 inclusive). The shaft 276 is adapted to be turned in the direction to turn the compass box to the right, viewing Fig. 7, by means of a pawl 280 that acts on a ratchet wheel 282 secured to the shaft 276. The shaft 276 is adapted to be turned in the direction to turn the compass box to the left by means of a pawl 284 that acts on a ratchet wheel 286 secured to the shaft 276. The pawls 280 and 284 are pivotally mounted on a pin 288 fixed in the end of an arm 290 loosely mounted on the shaft 276. The pawls 280 and 284 are normally held out of engagement with their respective ratchet wheels by means of a torsion spring 292 coiled about the upper end of the pivot pin 288 and secured thereto, the ends of the spring being secured in apertures in the ends of the pawls. The pawl carrying arm 290 is oscillated by means of a continuously rotating shaft 294 journaled in vertical bearings in the frame 278. The shaft 294 is driven by a horizontal shaft 296 through bevelled gears 298 secured to the ends of the shaft and the shaft 296 is driven 100 105 110 115 120 125 130

by the driving shaft of the apparatus through connections hereinafter described. The connection between the pawl carrying oscillating arm 290 and the shaft 294, comprises a link 300 connecting the pivot pin 288 with one end of a lever 302 pivoted on the upper end of a pin 304 mounted in the frame 278. The other arm of the lever 302 is provided with a stud that engages between sliding collars 306 mounted on a pin 308 that is mounted in the forked end of one arm of a bell crank lever 310. The collars 306 are urged inwardly against the stud on the lever 302 by means of springs 312 coiled about the pin 308 and interposed between the collars and the members of the forked end of the bell crank 310. The bell crank 310 is pivoted on the pin 304, and its other arm is bifurcated to operatively engage a cam 314 carried by the continuously rotating shaft 294. With this construction it will be apparent that the pawl carrying arm 290 is adapted to be oscillated once during each rotation of the shaft 294 and the movement imparted to the arm 290 will be yielding due to the yielding connection between the lever 302 and the bell crank 310.

The pawls 280 and 284 are independently moved into operative engagement with their respective ratchet wheels by means of electro-magnets 316 and 318 respectively. The connection between the electro-magnets and the pawls comprises an armature 320 pivoted on the pin 288 between the pawls and connected to the pawls by the ends of the spring 292 extending through slots 322 in oppositely extending arms of the armature. The armature 320 is held in the central position shown in Fig. 14 by the engagement of the ends of the springs with the right hand end walls of the slots 322. Upon energizing the electro-magnet 316 the armature is turned in a direction to carry the pawl 280 into engagement with its ratchet wheel 282 which acts to turn the shaft 276 in the direction to cause the vessel to be swung to starboard, and upon de-energizing the magnet 316, the spring 292 is permitted to swing the pawl 280 out of engagement with the ratchet wheel and to its normal ineffective position. Upon energizing the electro-magnet 318 the armature 320 will be turned in the direction to move the pawl 284 into engagement with the ratchet wheel 286 resulting in the shaft 276 being turned in the direction to cause the vessel to be swung to port.

The illustrated apparatus is provided with a course setting mechanism which by controlling the operation of the above described mechanism for changing the angular position of the compass box with relation to the vessel effects changes in the direction of travel of the vessel at the proper times to cause the vessel to traverse a predetermined course that has previously been laid out on

the course setting device. The course setting mechanism comprises three chart disks 326, 328 and 330 located above the top of the frame 278. The chart disk 326 forms the top of a drum 332 carried by the upper end 70 of a vertical shaft 334 extending through the top of the frame 278 and journaled in bearings in the frame. The shaft 334 is continuously driven by the shaft 294 through speed reducing gears comprising a worm 75 wheel 336 secured to the shaft 334 that engages a worm 338 carried by a horizontal shaft 340 having its ends journaled in the vertical sides of the frame 278. A worm wheel 342 is secured to the shaft 340 that 80 engages a worm 344 carried by the driving shaft 294.

The disk 328 forms the top of a drum 346 loosely mounted on the upper end of the pawl and ratchet driven shaft 276. The 85 disk 330 forms the top of a drum 347 loosely mounted on the upper end of a vertical shaft 348 journaled in bearings in the frame. Upon rotation of the shaft 276 the shaft 348 is rotated simultaneously in the same direction, the shaft 348 being connected to the shaft 276 by gears 350 and 352 secured to the shafts 276 and 348 respectively, which gears are connected by a pinion 354 loosely mounted on the upper end of a stud shaft 90 356 supported by the frame. Upon rotation of the shaft 276 to the left to swing the vessel to starboard, the disk 328 is rotated with the shaft, and upon rotation of the shaft 276 to the right to swing the vessel to port 100 the disk 328 is held stationary, while the disk 330 is rotated in the same direction as the shaft 276. The rotation of the disk 328 when the shaft 276 is turned to the left is accomplished by means of a spring pressed 105 pawl 358 mounted on a flange on the upper end of a sleeve 360 carried by the shaft 276, which pawl engages a ratchet wheel 362 secured to the underside of the disk carrying drum 346. The connection between the disk 330 and the shaft 348 comprises a spring 110 pressed pawl 364 mounted on a flange on the upper end of a sleeve 366 secured to the shaft 348, which pawl engages a ratchet wheel 368 secured to the underside of the 115 drum 347 that carries the disk 330. With this construction it will be apparent that during the rotation of the shaft 276 to the left the pawl 358 will act to turn the disk 328 to the left while no movement will be 120 imparted to the disk 330. During the rotation of the shaft 276 to the right the pawl 364 will act to turn the disk 330 to the right but no movement will be imparted to the disk 328. In order that one of the disks shall be held stationary against the drag of its pawl over the teeth of the ratchet wheel while the other disk is being rotated, a friction braking device is provided that tends to hold the disks stationary. This braking 125 130

device comprises a pair of straps 370 which engage the peripheries of the disk carrying drums 346 and 347. The straps 370 at one end are secured to a post 372 projecting from the top of the frame 278 and the other ends of the straps are connected by a coiled spring 374.

The chart disk 326 is provided with two series of equally spaced apertures 376 and 378 which are adapted to receive contact pins 380 and 382, respectively. The disk 326 and a pair of switch members 384 and 386 constitute a switch for opening and closing the circuits of the electro-magnets 316 and 318. The switch members 384 and 386 comprise levers pivotally mounted on a pin 388 that connects the upper ends of a pair of posts 390 mounted on the top of the frame 278. The levers are turned in the direction to urge their inner ends downwardly by means of springs 392 secured to the posts 390 and engaging the undersides of the outer ends of the levers. The switch members 384 and 386 are provided with contacts 394 and 396 in the form of a wire which are connected through spring contact brushes 398 and wires 400 and 402 to one pole of the magnets 318 and 316, respectively. The disk 326 is connected with the other pole of the magnets through a contact brush 404, comprising a spring post secured to the top of the frame 278 and engaging the periphery of the disk, a wire 406, the battery 117 and a wire 408 which is branched to the magnets. With this construction, it will be apparent from an inspection of the drawings that upon engagement of one of the pins 380 with the contact of the switch member 384 during the rotation of the disk 326, that the circuit of the electro-magnet 318 will be closed, whereupon the compass box will be turned in the direction to swing the vessel to starboard; and upon the pin 380 passing out of engagement with the contact of the switch member 384 the circuit will be opened. Upon engagement of one of the pins 382 with the contact of the switch member 386 the circuit of the electro-magnet 316 will be closed, whereupon the compass box will be turned in the direction to cause the vessel to swing to port until the circuit is opened by the pin 382 passing the contact of the switch member 386.

Assuming that the distance between the apertures of each series in the disk 326 indicate intervals of time of one minute duration, it will be apparent that by properly spacing the pins 380 and 382 about the disk that the compass box and hence the vessel may be swung to starboard or to port at any desired time. The number of degrees that the compass box is swung to starboard or port upon engagement of the pins carried by the disks 326 with the switch members 384 and 386 is controlled by the disks 328

and 330, the disk 328 as above described being connected to rotate with the shaft 276 during the rotation of the shaft in the direction to swing the vessel to starboard and the disk 330 being connected to rotate with the shaft 276 during the rotation of the shaft in the direction to swing the vessel to port. To this end, the disks 328 and 330 are each provided with a series of apertures 410 adapted to receive pins 412 and 414, respectively. During the rotation of the disks 328 and 330 the pins carried thereby are adapted to be brought into engagement with stop arms 416 and 418, respectively, which work between positive stop pins 420 secured to brackets 422 on the top of the frame. The engagement of a stop pin carried by one of the disks 328 and 330 with its associated stop arm 416 or 418, stops the disk in a position dependent upon the location of the pin on the disk, and hence through the ratchet and pawl connection with the compass box actuating shaft 276 stops the rotation of the shaft to limit the turning of the compass box, the yielding connection between the bell crank 310 and the lever 302 through which the shaft 276 is actuated permitting the bell crank to continue to oscillate without actuating the pawls 280 and 284. After the circuit of a magnet 316 or 318 has been broken, the stop arm is retracted from engagement with the stop pin and is then re-positioned so as to be engaged by the next stop pin that is carried by the disk 326 during the succeeding rotation of the disk.

From the foregoing, it will be apparent that upon engagement of one of the contact pins carried by the continuously rotating disk 326 with the contact on one of the switch members 384 and 386, the circuit including one of the electro-magnets 316 and 318 will be closed, whereupon the compass box will be turned in a direction to cause the vessel to be swung to port or starboard dependent upon which electro-magnet is energized by the closing of the circuit. The compass box will continue to turn in this direction until the rotation of the shaft 276 is stopped by a stop pin carried by one of the disks 328 and 330 being brought into engagement with its associated stop arm 416 and 418. In order to insure that the shaft 276 will continue to rotate until stopped by a stop pin carried by one of the disks 328 and 330, the relative timing of the rotation of the circuit controlling disk 326 and shaft 276 is such that a circuit including an electro-magnet 316 or 318 is held closed by a contact pin carried by the disk riding in contact with its associated switch member 380 or 386 until the shaft 276 would, if not stopped by one of the stop disks 328 and 330, make substantially a complete revolution.

To enable the stop arm 416 to be operated in the manner above described, the arm is pivotally mounted on one arm of a bell crank 424 pivoted on one of the brackets 422 and the other arm of the bell crank is connected by a link 426 with a lever 428. The lever 428 is urged in a direction to position a cam lug formed on its free end into the path of pins 430 inserted in one or more of a series of apertures 432 in the disk 326, by means of a coiled spring 433 connected with the lever. Upon engagement of one of the pins 430 with the end of the lever 428, the stop arm 416 is retracted out of engagement with the adjacent stop pin on the disk 328 and a leaf-spring 434 engaging the free end of the arm presses the arm back against the other stop pin 420. When the pin 430 has passed by the end of the arm 428, the spring 433 acts to turn the lever 428 in the direction to again move the stop arm 416 into the path of the pins carried by the disk 328 and a bevelled surface on the end of the arm causes the arm to ride behind the stop pin so that the arm will be in position to be engaged by a second stop pin during the next rotation of the disk.

The stop arm 418 is pivotally connected at its rear end to a bell crank 436 pivoted on the bracket 422. The other arm of the bell crank is connected by a link 438 with one arm of a lever 440, the other arm of which lever is connected by a link 442 with one arm of a bell crank 444 pivoted on the top of the frame. A cam lug is formed on the end of the other arm of the bell crank 444 and is held in the path of pins 446 inserted in one or more of a series of apertures 448 in a flange 449 formed on the underside of the drum 332 carrying the disk 326, by a spring 450 connected with the lever 440. Upon engagement of a pin 446 with the end of the bell crank 444, the stop arm 418 is retracted, and upon disengagement of the pin from the bell crank the spring 450 acts to return the stop arm into position to the rear of the stop pin carried by the disk 330.

It will be understood from the foregoing, that by properly arranging the contact pins on the disk 326, stop pins on the disks 328 and 330, and stop arm controlling pins on the disk 326 and the flange 449, that the apparatus may be set to cause the vessel to travel a given course of several legs and that should the vessel be swerved from the given course by winds, currents, tides or other forces, the compass controlled mechanism would immediately act to restore the vessel to the course.

The driving shafts 296 and 178 of the course setting mechanism and the compass controlled mechanism, respectively, are driven by the driving shaft 16 of the rudder actuating mechanism. The connection between the shafts 16 and 296 comprises a

belt 452 (Fig. 1) that passes over pulleys secured to the shafts and suitably arranged guide pulleys 454. The connection between the shafts 16 and 178 comprises a belt 456 passing over pulleys secured to the shafts 178 and 296 and suitably arranged guide pulleys 458.

While the features described herein are well adapted for use in a steering apparatus, it is to be understood that, except as defined in the claims, certain features of the present invention are not limited to use in an apparatus of this type.

The nature and scope of the present invention having been indicated and an apparatus embodying the several features of the invention in their preferred form having been specifically described, what is claimed is:

1. A controlling apparatus for a moving object having, in combination, a guiding device movable relatively to the object in opposite directions from normal position to change the direction of travel of the object, mechanism acting when thrown into operation to move the guiding device relatively to the object, to maintain the guiding device in the position moved until the direction of travel of the object has been changed a predetermined amount and to then return the guiding device to its normal position and means acting automatically to throw said mechanism into operation and to throw said mechanism out of operation when the guiding device has been returned to normal position.

2. An apparatus for maintaining a moving object on a given course having, in combination, a guiding device movable relatively to the moving object in opposite directions from normal position to change the direction of travel of the object, mechanism acting to move the guiding device to a predetermined position relatively to the object upon deviation of the object from the course, to maintain the guiding device in this position until the object has been restored substantially to the course, and to then return the guiding device to its normal position, and means acting automatically to throw said mechanism out of operation when the guiding device has been returned to normal position.

3. An apparatus for maintaining a moving object on a given course having, in combination, a guiding device movable relatively to the moving object in opposite directions from normal position to change the direction of travel of the object, a compass, and mechanism controlled by the compass acting when thrown into operation to move the guiding device relatively to the object upon deviation of the object from the course, to maintain the guiding device in the position moved until the object has been restored substantially to the course, and to

then return the guiding device to its normal position, and means acting automatically to throw said mechanism out of operation when the guiding device has been returned to normal position.

4. A controlling apparatus for moving objects having, in combination, a guiding device movable relatively to the moving object in opposite directions from normal position to change the direction of travel of the object, a course setting means, mechanism controlled by the course setting means acting when thrown into operation to move the guiding device relatively to the object at a predetermined point in the travel of the object, to maintain the guiding device in the position moved until the direction of travel of the object has been changed a predetermined amount, and to then return the guiding device to its normal position, and means acting automatically to throw said mechanism out of operation when the guiding device has been returned to normal position.
5. An apparatus for maintaining a moving object in a predetermined angular position having, in combination, a guiding device movable relatively to the moving object in opposite directions from normal position to change the angular position of the moving object, mechanism acting to move the guiding device relatively to the object upon deviation of the object from its predetermined angular position, to maintain the guiding device in the position moved until the object has been substantially restored to the predetermined angular position, and to then return the guiding device to its normal position, and means acting automatically to throw said mechanism out of operation when the guiding device has been returned to normal position.

6. A controlling apparatus for a moving object having, in combination, a guiding device movable relatively to the object to change the direction of travel of the object, a compass, a compass box, means for turning the compass box to the right and to the left to change the angular position of the compass box relatively to the object, and connections between the guiding device and the compass box for moving the guiding device relatively to the object upon a change in the angular position of the compass box in either direction relatively to the object.

7. A controlling apparatus for a moving object having, in combination, a guiding device movable relatively to the object to change the direction of travel of the object, a compass, a compass box, means for turning the compass box to the right and to the left to change the angular position of the compass box relatively to the object, and electrically controlled connections between the guiding device and the compass box

for moving the guiding device relatively to the object upon a change in the angular position of the box in either direction relatively to the object.

8. A controlling apparatus for a moving object having, in combination, a guiding device movable relatively to the object to change the direction of travel of the object, a compass, a compass box, connections between the guiding device and compass box to move the guiding device relatively to the object upon a change in the angular position of the compass box relatively to the object, and means for changing the angular position of the compass box relatively to the object to cause the object to travel a predetermined course consisting of a plurality of legs, one or more of which extend to the right and one or more of which extend to the left of the preceding leg.

9. A controlling device for a moving object having, in combination, a guiding device, and automatically controlled means for alternately turning the guiding device in opposite directions at predetermined times comprising a shaft, connections between the shaft and the guiding device, means for rotating the shaft comprising a pair of electro-magnets, one of which when energized effects the rotation of the shaft in one direction, and the other one when energized effects the rotation of the shaft in the opposite direction, and means for energizing and de-energizing the magnets.

10. A controlling apparatus for a moving object having, in combination, a guiding device, means for alternately turning the guiding device in opposite directions comprising a shaft, connections between the shaft and guiding device, a pair of driving members rotated in opposite directions, a clutching device for alternately connecting and disconnecting the driving members and shaft and means acting automatically at predetermined times to actuate the clutching device.

11. A controlling apparatus for a moving object having, in combination, a guiding device, a driving mechanism for turning the guiding device in opposite directions, and means for automatically controlling the operation of the driving mechanism, comprising a constantly reciprocating rod, a pair of pawls carried by the rod, one of the pawls adapted to be connected to the driving mechanism to adjust the mechanism to turn the guiding device in one direction and the other pawl adapted to be connected to the driving mechanism to adjust the mechanism to turn the guiding device in the opposite direction, and automatically controlled means for independently connecting and disconnecting the pawls and driving mechanism.

12. A controlling apparatus for a moving

object having, in combination, a guiding device movable relatively to the object to change the direction of travel of the object, a compass, a compass box, a gage device mounted to swing with the compass, a feeler cooperating therewith, means controlled by the feeler for actuating the guiding device to restore the object to its course upon a deviation therefrom, and means for moving the compass box relatively to the object.

13. A controlling apparatus for a moving object having, in combination, a guiding device movable relatively to the object to change the direction of travel of the object, an arm adapted to be moved to at least three definite positions, a compass, power operated means controlled by the compass for moving the arm from one position to another upon deviation of the object from the course, and connections between the arm and guiding device to move the guiding device to a definite position dependent upon the position of the arm and for holding the guiding device in the position moved until the object has been restored to its course.

14. A controlling device for a moving object having, in combination, a rudder, an arm adapted to be moved to at least three definite positions, connections between the arm and rudder to move the rudder to neutral position when the arm is in its intermediate position and to move the rudder to starboard and port when the arm is in the other positions respectively, and power operated means controlled by the compass for automatically moving the arm from one to another position to maintain the object on a given course.

15. A controlling apparatus for a moving object having, in combination, a rudder, a compass, connections between the compass and rudder for controlling the position of the rudder, a compass box, two movable members, connections between the compass box and the movable members to turn the box in one direction upon movement of one of the members, and in the opposite direction upon movement of the other member, and means for actuating and controlling the movable members to cause the object to traverse a given course.

16. A controlling apparatus for a moving object having, in combination, a rudder, a compass, connections between the compass and rudder for controlling the position of the rudder, a compass box, two movable members, connections between the compass box and the movable members to turn the box in one direction upon movement of one of the members and in the opposite direction upon movement of the other members, a continuously rotating member, and means cooperating therewith for actuating and controlling the movable members to cause the object to traverse a given course.

17. A controlling apparatus for a moving object having, in combination, a rudder, a compass, connections between the compass and rudder for controlling the position of the rudder, a compass box, two intermittently movable members, connections between the compass box and the movable members to turn the box in one direction upon movement of one of the members, and in the opposite direction upon movement of the other member, two electro-magnets, means controlled by the electro-magnets for actuating the movable members respectively, and means for independently energizing and de-energizing the magnets at predetermined times to cause the object to traverse a given course.

18. A controlling apparatus for a moving object having, in combination, a rudder, a compass, a compass box movable angularly relatively to the object, connections between the compass box and rudder to turn the rudder in opposite directions upon movement of the compass box in opposite directions respectively, two movable members, connections between the compass box and the movable members to turn the compass box in one direction upon movement of one of the members, and in the opposite direction upon movement of the other member, and means for actuating and controlling the movable members to cause the object to traverse a given course.

19. A controlling apparatus for a moving object having, in combination, a guiding device movable relatively to the object to change the direction of travel of the object, a compass, a compass box, mechanism for turning the compass box to the right and to the left to change the angular position of the compass box relatively to the object, connections between the compass box and the guiding device for moving the guiding device relatively to the object during the turning movement of the compass box, and a course setting mechanism comprising means for controlling the operation of the mechanism for turning the compass box to cause the compass box to be turned in one direction or the other at a predetermined time in the travel of the object, and means for stopping the turning movement of the compass box when it has reached a predetermined angular position in relation to the object.

20. A controlling mechanism for a moving object having, in combination, a guiding device, a source of power, actuating mechanism therefrom acting when thrown into operation to move the guiding device independently of the movement of the object, and controlling devices acting automatically upon displacement of the object from normal position, to cause the actuating mechanism to move the guiding device in a direction to restore the object, and to return the guiding

device to neutral position upon the return of the object to normal position.

21. A controlling device for moving objects having, in combination, a rudder, a compass, an arm controlled from the compass, movable to at least three positions, a separate electric circuit controlled by said arm in each of said three positions, and rud-

der actuating mechanism controlled by said circuits acting to move the rudder to neutral position when the arm is in its intermediate position and to move the rudder to starboard and to port when the arm is in the other positions, respectively. ¹⁰

ERASTUS E. WINKLEY.
